UNITED STATES PATENT OFFICE.

WILLIAM NOAH ALLYN, OF AUBURN, NEW YORK.

SURGICAL INSTRUMENT.

Application filed February 25, 1925. Serial No. 11,495.

This invention relates to a surgical instrument, technically known as a sigmoidoscope or proctoscope to be used in the examination of the rectum, pelvic colon, sigmoid flexure, descending colon, and other canals, channels or ducts, for locating possible pathological troubles and permitting curative remedies to be applied to the affected parts.

The main object is to provide a device of this character which may be inserted into the affected duct with the least possible irritation or inconvenience to the patient and at the same time to provide said device with means whereby the affected part may be accurately located and properly treated through an opening in the implement while the latter still remains in the channel or duct.

Another object is to provide the distal end of the device with a longitudinally tapered beak or obturator of rounded cross section but slightly concaved longitudinally on one side and convexed along its opposite side so that it may be used more effectively for distending or dilating strictures or other contracted portions of the channel or duct into which it is inserted without liability of lacerating the tissue walls thereof.

Another object is to provide the proximal end or hilt of the outer tube or sheath of the device with a suitable cup-guard or stop plate constructed in such manner as to support the device against lateral rolling displacement upon a table or equivalent support and in a convenient position for grasping by hand when not in actual use, and to prevent excessive entrance into the duct.

A further object is to provide the distal end of the device with a relatively small but powerful electric lamp arranged in such manner as to direct its rays over a relatively wide range of the channel or duct into which the device is inserted when the closed beak or obturator is removed without obstructing a clear vision of the walls of said channel or duct through the proximal end of the elongated tube.

A still further object is to extend the lamp conductor to a point near the proximal end of the device and to provide means whereby said conductor may be conveniently attached to and detached from a source of electric energy without disturbing any of the other parts of said device.

Another object is to provide the distal end of the device with a relatively small

mirror and to enable said mirror to be adjusted rotarily or longitudinally of the tube for convenience in locating diseased or injured parts of the duct into which the tube is inserted.

Another object is to provide the proximal end of the device with a window or lens or both window and lens capable of being moved to and from a position across the adjacent end of the sight opening through the tube to be used or displaced as may be necessary or more convenient for the purpose of examination of the affected parts.

Other objects and uses relating to specific parts of the device will be brought out in the following description.

In the drawings:

Figure 1 is a perspective view of a surgical instrument embodying the various features of my invention.

Figure 2 is an enlarged longitudinal sectional view, partly broken away of the same device.

Figure 3 is an enlarged sectional view, through one end of the device, taken on line 3—3, Figure 1.

Figure 4 is a transverse sectional view taken in the plane of line 4—4, Figure 2.

Figure 5 is a perspective view of the detached outer tube or sheath.

Figure 6 is a perspective view of the detached inner tube.

Figure 7 is a perspective view of the detached beak or obturator.

Figure 8 is a side elevation of the removable coupling section for connecting and disconnecting the electric terminal connection of the lamp to and from the electric source of energy.

Figure 9 is a perspective view, partly in section of the distal end of the inner tube showing the relative positions of the lamp and mirror and the opening in one side of the tube.

As illustrated this device comprises a cylindrical outer tube or sheath —1— having at its proximal end a hilt —2— provided with a surrounding cup guard or stop plate —3— which is formed with a corrugated edge to provide suitable feet —4— adapted to rest upon a table or equivalent support to hold the device against turning displacement and in a convenient position to be grasped by the hand when not in actual use.

The distal end of the outer tube or sheath —1— is bevelled at —5— to facilitate its

- entrance into the colon or other duct and is provided with lengthwise graduations —6— to determine the degree of entrance of the device into the affected part.
- 5 An inner tube —7— is telescopically inserted into the proximal end of the tubular sheath —1— extends the greater portion of the length thereof and to fit snugly therein to permit the relative rotation and axial 10 movement of both stops, said inner tube being provided with an enlarged hilt —8— forming a shoulder —9— adapted to engage the adjacent end face of the tube —1— for limiting their telescopic movement one upon 15 the other.
- The outer end face of the tube —1— is provided with a notch or recess —10— for receiving a shoulder —11— on the inner end of the hilt —8— of the tube —7— and 20 thereby affording a convenient means for locking the two tubes to each other against relative rotary movement when the inner tube is inserted to the limit of its movement within the outer tube.
- 25 The extreme outer end of the inner tube —7— is provided with an outwardly projecting annular flange —12— forming a supporting end guide for a suitable bezel —13— which is pivoted by a screw —14— to the flange —12— at one side of the opening through the tube and has its opposite side engaged in a grooved projection —15— on the flange —12— when the bezel is closed.
- 30 This bezel receives and supports a transparent window —16— which when the bezel is closed is alined with the opening in the top —7— to permit clear vision from the proximal end through and to the distal end of said tube.
- 35 A relatively smaller bezel —17— is pivoted by the bolt —14— to the bezel —13— and to the flange —12— to swing to and from a position across the outer face of the window —16— and contains a plane or 40 magnifying lens —18— which together with its supporting bezel —17— may be used in connection with the window —16— for visualizing objects at the distal end of the tube or by swinging the bezel —13— and its window —16— out of registration with the opening in the tube —7— the bezel —17— and its lens —18— may be used independently of the window.
- 45 In some instances however both of the bezels may be swung out of registration with the opening in the tube —7— to permit the natural vision of the objects at the distal end of the tube.
- 50 A portion of one side of the tube —7— is cut away at —19— a circumferential distance less than a quarter of said circumference and extending inwardly some distance from the distal end thereof to form an opening for the passage of light therethrough as 55 may be required for the examination of 60 affected parts of an affected colon or other duct into which the device is inserted and also for receiving the cylindrical end of a beak or obturator —20—.
- The opposite side of the distal end of the tube —7— is provided with a relatively short lengthwise slot —21— for receiving an electric lamp bulb —22— which is inserted in a suitable supporting socket —23— on the interior of the adjacent portion of 65 the tube, the side walls of the slot —21— serving as more or less protection to the lamp bulb —22—.
- The distal ends of the edges of the opposite side walls of the slot —19— are beveled 70 at —24— across the axis to the extreme inner end of the tube to enable the light rays from the lamp —22— to extend over a relatively wide range.
- 75 One of the wires —22'— of the lamp circuit extends from the lamp socket toward the proximal end of the tube —7— and beyond the shoulder —9— along the interior of the corresponding side of the tube enclosed in a relatively small tube —25— 80 which is secured to the inner face of the adjacent side of the tube —7— and carries at its distal end the socket —23—, the wire —22— being insulated throughout its length from the tube —25—.
- 85 The other terminal of the lamp filament is electrically connected to its base which when secured in the socket —23— is electrically connected thereto and to the tube —7— which forms one of the conductors to 90 the lamp to complete the lamp circuit.
- 95 The tubular members —1— and —7— and obturator —20— are preferably made of thin non-corrodible metal for sanitary purposes and are provided with smooth external finish to facilitate their entrance into the colon or other duct.
- 100 The beak or obturator —20— is preferably composed of an inner cylindrical section —26— and an outer section —27— fitted 105 one within the other by brazing or equivalent fastening means, the cylindrical section —26— being provided on one side with a lengthwise slot —28— extending some distance forwardly from its outer end for receiving the lamp —22— when the parts are assembled for use, said cylindrical portion —26— being extended some distance beyond the corresponding end of the section —27— to closely engage the inner walls of the adjacent end of the tube —7—.
- 110 One side of the proximal end of the section —27— adjacent the slot —28— is cut away to form bevel edges —29— corresponding to the bevel edges —24— on the distal 115 end of the section —7— and these beveled edges —29— are provided near their outer ends with recesses —30— and projections —31—, both of which are rounded longitudinally for interlocking engagement with 120
- 125

similar projections and recesses —30'— and —31'— on the distal edges on the opposite walls of the slot —19— in the section —7— when the parts are assembled one within the other.

For example, in assembling the beak or obturator —27— in the distal end of the tubular section —7— the tubular extension —26— is first inserted into the distal end of the section —7— with the slot —28— alined with the lamp —22— and its socket —23— until the shoulders —31— of the section —27— ride against the shoulders —30'— of the section —7— and then by continuing the inward pressure of the section —27— the shoulders —31— will ride over the shoulders —30'— until they enter the recesses —31'— at which time the shoulders —30'— will enter the recesses —30—, it being understood that the walls of the distal end of the slot —19— are sufficiently resilient to permit this interlocking engagement of the shoulders —31— and —30'— in their respective recesses —31'— and —30— and that when the parts are thus interlocked the beveled edges —24— of the section —7— fit closely against the corresponding beveled edges —29— of the section —27— thereby producing a substantially smooth external surface at the joints.

The resiliency of the opposite walls of the slot —19— serve to yieldingly hold the parts —7— and —27— in interlocking engagement against relative axial rotary movement and also hold them in axial alinement but when the tube —7— with the obturator —20— interlock with its distal end inserted in the outer tube or sheath the distal end of the latter extends beyond the locking joint between the sections —7— and —27— and additionally hold them in interlocking engagement against relative axial or circumferential displacement.

A small mirror —32— is mounted on the distal end of a supporting stem —33— which, in turn, is slidably and rotatably mounted in a relatively small guide tube —34—, the latter being lengthwise of and within the distal end of the tubular section —7— and rigidly secured thereto by brazing or equivalent fastening means.

The mirror —32— is sufficiently small to pass within the tubular end of the beak —27— and is preferably disposed at an obtuse angle with the stem end adjustable rotarily as well as axially so as to reflect the rays of the lamp —22— through the open side of the slot to enable the operator to examine more closely the affected part into which the device is inserted through the open proximal end of said device or through the windows —16— or —18— as may be desired.

The distal end of the section —27— is preferably tapered and closed at its smaller end but its outer surface is smoothed and rounded in cross section, one side thereof

being concave longitudinally at —35— while the opposite side is preferably convexed at —36— which permits the beak to more easily distend or dilate the affected part into which it is inserted without excessive irritation or inconvenience to the patient.

The hilt —8— of the tube —7— carrying the electric conducting tube —25— is provided with an outwardly extending nipple —37— containing the terminal electric contact member —38— of the conductor —22'— of the lamp and also adapted to receive a suitable coupling by which it may be connected to a source of electrical energy.

This coupling comprises a metal head —39— having reduced tubular extension —40— adapted to slide over and upon the nipple —37—, said head being also provided with the usual axially yielding contact member —41— for engagement with the contact —38— for completing the closing of the lamp circuit when the parts are assembled.

A sleeve —42— is slidable axially of and upon the head —39— and is provided at its inner end with an inturned flange —43— surrounding the reduced end —40— to form a set for a retracting spring —44— which is interposed between the flange —43— and inner end of the head —39— for normally urging the sleeve inwardly.

The reduced portion —40— of the head —39— is provided with a slot —45— extending lengthwise thereof from its inner end for receiving a radially projecting pin —46— on the adjacent side of the nipple —37—, one of the walls of said slot being provided with a laterally projecting recess —47— which is also adapted to receive the pin for locking the reduced portion —40— on the nipple —37— when the coupling is assembled thereon.

The sleeve —42— is provided with an axially projecting tongue —48— slidable in the slot —45— across the lateral recess —47— as the sleeve —42— is moved endwise and holds the sleeve and head —39— against relative turning movement, said sleeve being provided with a screw projecting into an annular groove in the head —39— as shown in Figure 2 to prevent endwise displacement of the sleeve from the head.

The inner end of the tongue is provided with a cam face —50— which, when the coupling is placed upon the nipple —37— rides against the pin —46— thereby forcing the sleeve —42— outwardly against the action of its retracting spring —44— until the recess —47— is registered with said pin at which time the pin is caused to enter the recess at one side of the tongue —48— thereby allowing the sleeve —42— and its tongue to be forced inwardly by the spring —44— to lock the pin in the recess and to hold the coupling in operative connection with the nipple —37—.

To remove the coupling from the nipple it is simply necessary to draw the sleeve —42— outwardly by hand against the action of the spring —44—, thereby withdrawing the tongue —48— beyond the pin —47— and allowing the latter to enter the slot —45— and pass through the open end of the slot.

An air inlet nipple —51— is secured to the hilt of the tubular section —7— and is adapted to be connected by a flexible pipe —52— to an air compressor for supplying air to the interior of the tubes in case it may be desired to further distend or dilate the colon or other duct into which the instrument is inserted.

Operation.

When the various sections of the device are assembled in the manner shown in Figures 1 and 2 they may be inserted to any degree indicated by the graduations —6— into the colon or other duct to be examined between the guard plate —3— and distal end of the section —36— and after the affected part has been distended the required amount for examination the tubular sheath —1— may be left in the duct and the section —7— together with the beak —8— and other parts carried thereby may be entirely withdrawn from the sheath to permit the removal of the beak or obturator —36—.

Immediately following the removal of the beak the inner tubular section —7— may be reinserted in the sheath —1— and its lamp circuit connected to a source of electric energy for illuminating the interior of the duct and permitting a more thorough examination of the various parts thereof, it being understood that the rays of light from the lamp —22— are free to radiate through the opening —19— aided by the mirror —32—.

The parts to be examined may then be inspected through the opening in the proximal end of the tube —7— with or without the use of either of the lens —16— or —18—.

When the affected part of the colon or duct is located suitable treatment may be applied through the tube by simply adjusting the tubes to bring the opening —19— into registration with the affected part.

When the diseased part is properly treated the tubes may be withdrawn and separated one from another for properly cleansing and sterilizing ready for repetition of the operation.

What I claim is:

1. A surgical instrument of the character described, comprising a tubular section and an obturator section detachably interlocked with the distal end of the tubular section and provided with a smooth unbroken and continuous surface.

2. In a device of the character described, a tubular section having a longitudinal slot in one side, opening from its distal end, an obturator telescoping with said distal end, and a sheath telescopically inclosing the joined ends of the tube and obturator.

3. In a device of the character described, a tubular section having a longitudinal slot in one side, opening from its distal end, an obturator telescoping with said distal end, and a sheath telescopically inclosing the joined ends of the tube and obturator, the adjoining ends of said tube and obturator being provided with frictionally interlocking members to hold them against axial displacement while the sheath serves to hold them against radial displacement.

4. In a surgical instrument of the character described, a tube having means at one end for receiving and supporting an obturator, said tube being provided with an air inlet for admitting air through the interior of the tube to the part being treated when the obturator is removed.

In witness whereof I have hereunto set my hand this 7th day of February, 1925.

WILLIAM NOAH ALLYN.
